UNITED STATES PATENT OFFICE.

ALBERT P. COCHRANE, OF NEW YORK, N. Y.

COMBINED CHIN-TRUSS AND EAR-COMPRESS.

1,099,967.

Specification of Letters Patent. Patented June 16, 1914.

Application filed August 15, 1913. Serial No. 784,893.

To all whom it may concern:

Be it known that I, ALBERT P. COCHRANE, a citizen of the United States, and a resident of New York, in the county and State of the 5 same name, have invented a certain new and useful Improvement in Combined Chin-Trusses and Ear-Compresses, of which the following is a specification.

This invention relates to improvements in 10 devices for supporting the chin and confining the ears of adults and children and the objects are, first, to provide means whereby the wearer's chin is held with respect to the head so that the mouth is kept closed, and a 15 second object is to confine protruding ears flat against the head.

These objects are attained by the novel construction and arrangement of parts hereinafter described and shown in the accompanying 20 drawings, forming part of this specification, and in which:

Figure 1 is a perspective view of the appliance and illustrating its application. Fig. 2 is a similar view of the same, unapplied 25 but extended as in use, and, Fig. 3 is a front elevation of the ear confining member and its connections.

It is well known that many diseases of 30 the nose, throat and bronchial passages are aggravated, or even caused, by the uncleanly and unhealthy custom of breathing through the mouth rather than the nostrils, as intended by nature, and that the obnoxious habit of snoring can only occur when the 35 mouth is open.

This appliance is intended to compel the proper use of the nose, particularly during slumber, preventing sagging of the lower jaw, and hence snoring, dryness of the throat 40 and mucous passages connected therewith, ultimately restoring the muscles of the throat, jaw and face to healthy activity, effecting a permanent cure for mouth breathing and the attendant ills therefrom, without 45 discomfort or inconvenience to the wearer. The appliance is furthermore adapted to overcome the unsightly appearance of outwardly protruding ears by exerting a gentle pressure upon them tending to 50 train the ear muscles conformably inward to a proper and more desirable appearance.

The invention consists of a chin support or sling 10, of any preferred textile fabric, as silk, linen, or cotton, cut and formed to 55 the required shape and provided at its ends

with side members 11 and 12, spaced respectively at the front and rear. To these are securely attached the ends of stays or tapes arranged in pairs 13 and 14, adapted to extend upward along the side of the face and head, one in front of, and the other behind the ear, and adjustably engage with clips 15 secured to a crown piece 16, either directly, or indirectly through the medium of reinforcing tapes 17 affixed thereto. The crown 60 piece 16 consists of an elliptical band integrally formed from material of the same nature as that of the chin support, shaped and adapted to suit the top of the head on which it is disposed. Side members or ear 65 confining plates 20, also formed from like material in any preferred shape, as the disk shown, and provided with a central opening 21, are arranged to contact with the exterior of the ear; these members are further 70 provided with projections or tabs 22 at each end, the same having a pair of longitudinal slits 23 through which are passed the stays 13 and 14 in such manner as to support and press the ear plates against the side of the 75 head; these plates are vertically adjustable upon the stays, with which they frictionally engage, by means of their peculiar connections.

In originally adjusting the appliance to 80 the head of the wearer, the stays are first loosened, but not entirely disengaged from their corresponding clips, the crown piece and chin support placed in position, the stays drawn up and tightened in the clips, 85 and adjusted to afford the pressure effect required, which is never sufficient to cause the least discomfort, inconvenience or interference with conversation or the act of swallowing; once the correct adjustment has been obtained, the appliance may be slipped on or off without loosening or the trouble of further adjustment.

Thus I provide a remedial appliance at 90 small cost, capable of being laundered and used indefinitely as there are no rubber or other elastic parts to deteriorate and destroy its usefulness.

Having thus described my invention, what I claim as new and desire to secure by Letters Patent, is:

In an appliance of the class described, the combination with a head piece to rest on top of the head, of a chin strap to fit under the chin, pairs of substantially parallel stays 110

connecting said head piece and chin strap on each side, one of the stays of each pair adapted to lie in front and the other in rear of the ear, means for varying the operative length of each of said stays to adjust the chin strap with respect to the head piece, and ear pieces, one mounted to slide substantially vertically on each pair of stays, whereby it is adjustable independently of the chin straps to accommodate the appliance to

heads having different dimensions and variously disposed features.

In testimony whereof I have signed my name to this specification in the presence of two subscribing witnesses.

ALBERT P. COCHRANE.
